Patented Apr. 19, 1960

187,690

INFLATABLE EXHIBIT HALL

Kenneth E. Joy, Vienna, Va.

Application April 24, 1958, Serial No. 50,610

Term of patent 14 years

(Cl. D13—1)

(Granted under Title 35, U.S. Code (1952), sec. 266)

Des. 187,690

PAGE 2

FIG. 2

Fig. 3.

The design described herein may be manufactured and used by or for the Government for governmental purposes without the payment of any royalty thereon.

Fig. 1 is a front elevational view of an inflatable exhibit hall showing my new design;

Fig. 2 is a perspective view of the same exhibit hall; and
Fig. 3 is a top plan view.

The essential features of my design reside in the portions shown in full lines.

I claim:

The ornamental design for an inflatable exhibit hall, as shown and described.
